ABSTRACT: An electric timing circuit to prevent the battery of a test instrument from being discharged if the instrument is left switched on when not in use. An amplifier and a capacitive element connected across the input circuit of the amplifier so that when the battery is connected across the capacitive element, the capacitive element charges up to effect closure of a current path through the circuit, and when the battery is disconnected from across the capacitive element, the capacitive element discharges thereby breaking the current path through the circuit after an interval determined by the rate of fall of the voltage across the capacitive element.

ELECTRIC TIMING CIRCUITS

This invention relates to electric timing circuits.

According to the present invention an electric timing circuit includes an amplifier comprising first and second junction transistors of like conductivity type each having a base, an emitter and a collector electrode, the collector electrodes of the first and second transistors being directly connected together, the emitter electrode of the first transistor being directly connected to the base electrode of the second transistor, the base electrode of the second transistor, the base electrode of the first transistor being connected in the input circuit of the amplifier, and the emitter electrode of the second transistor being connected in the output circuit of the amplifier; a capacitive element connected across the input circuit of the amplifier; and a third junction transistor, of the same conductivity type as the first and second transistors, and having a base, an emitter, and a collector electrode, the base electrode of the third transistor being directly connected to the emitter electrode of the second transistor, the arrangement being such that when an electric supply of predetermined voltage is connected across the capacitive element, the capacitive element charges up and the third transistor is rendered conductive, and when the supply is disconnected from across the capacitive element, the capacitive element discharges at least in part by way of the base electrode of the first transistor, and the third transistor is rendered nonconductive after an interval determined by the rate of fall of the voltage across the capacitive element.

Preferably the first, second, and third transistors are NPN-type junction transistors.

The third transistor can be used as a switch, the emitter-collector path of the third transistor being connected in a supply lead from a voltage source to a load.

One embodiment of an electric timing circuit in accordance with the present invention will now be described by way of example with reference to the accompanying drawing, which is a circuit diagram of an arrangement for protecting the battery of a portable electric test instrument from being completely discharged through the instrument being left switched on when not in use.

As shown in the drawing, the circuit includes an amplifier comprising two NPN junction transistors Q_1 and Q_2 having their collector electrodes directly connected together, and connected by way of a resistor R_4 to a positive supply lead. The emitter electrode of the transistor Q_1 is directly connected to the base electrode of the transistor Q_2 . The emitter electrode of the transistor Q_2 is directly connected to the base electrode of a third NPN junction transistor Q_3 , the emitter-collector path of the third transistor Q_3 being connected in a negative supply lead. A series arrangement of a pushbutton switch S_2 and two resistors R_1 and R_2 is connected between the positive and negative supply leads, the junction between the resistors R_1 and R_2 being connected by way of a resistor R_3 to the base electrode of the transistor Q_1 . A capacitor C_1 is connected between the junction between the resistors R_1 and R_2 and the negative supply lead. A battery B is connected across the positive and negative supply leads, a switch S_1 being connected between the positive pole of the battery B and the positive supply lead. The positive and negative supply leads are connected to a load L .

In the rest state the switches S_1 and S_2 are open, the transistors Q_1 , Q_2 and Q_3 are all nonconductive, and no power is supplied from the battery B to the load L . When the switch S_1 is closed, still no power is supplied from the battery B to the

load L as the transistor Q_3 is nonconductive and thus serving as an open switch in the negative supply lead. If now the switch S_2 is closed, the capacitor C_1 charges up to the voltage of the battery B , and all of the transistors Q_1 , Q_2 and Q_3 are rendered conductive, the transistor Q_3 becoming saturated. The transistor Q_3 is now functioning as a closed switch, and power is supplied from the battery B to the load L . When the switch S_2 is released to open, the voltage across the capacitor C_1 maintains the transistors Q_1 , Q_2 and Q_3 conductive, and power continues to be supplied from the battery B to the load L . The capacitor C_1 now discharges at least in part by way of the base electrode of the transistor Q_1 , and by way of the resistor R_2 . When, after a certain interval the voltage across the capacitor C_1 falls to a certain value, the transistors Q_1 , Q_2 and Q_3 are rendered nonconductive, the transistor Q_3 now again functioning as an open switch, and power ceases to be supplied from the battery B to the load L . If the switch S_2 is now again closed and released, the circuit effects a further cycle of operation as described above. Thus, although the switch S_1 remains closed, power is supplied from the battery B to the load L for a maximum continuous time determined by the rate of fall of the voltage across the capacitor C_1 .

In one circuit as described above, the components had the following values:

25

$R_1=330$ ohms
 $R_2=10$ megohms
 $R_3=4.7$ megohms

$R_4=3.9$ k. ohms
 $C_1=100$ mfd. (electrolytic)
 Battery (B) voltage=9 volts

30 this circuit maintaining a supply of power from the battery B to the load L for approximately 30 minutes after the switch S_2 was opened. The current supplied to the load L from the battery B remained substantially constant until the voltage across the capacitor C_1 had fallen to 2 volts, the current supplied then decreasing until the voltage across the capacitor C_1 was 1½ volts, when substantially no current was supplied.

35 The time for which power is supplied from the battery B to the load L after the switch S_2 is opened can be increased by increasing the voltage of the battery B or by increasing the capacitance of the capacitor C_1 .

40 If desired, the transistors Q_1 , Q_2 and Q_3 , and resistors R_1 , R_2 , R_3 and R_4 can be provided in integrated circuit form.

What is claimed is:

- 45 1. An electric timing circuit arrangement including an amplifier comprising first and second junction transistors of like conductivity type each having a base, an emitter and a collector electrode; means directly connecting the collector electrodes of the first and second transistors; means directly connecting the emitter electrode of the first transistor to the base electrode of the second transistor; means connecting the base electrode of the second transistor to one terminal of a capacitive element; a third junction transistor of the same conductivity type as the first and second transistors and having a base, an emitter and a collector electrode; means directly connecting the emitter electrode of the second transistor to the base electrode of the third transistor; means connecting the emitter electrode of the third transistor to the other terminal of the capacitive element; an output terminal connected to the collector electrode of the third transistor, a first input terminal connected to said other terminal of the capacitive element; a second input terminal and a network including a switch, said network being connected between the first and second input terminals and connected to said one terminal of the capacitive element to provide a predetermined voltage across the capacitive element.
